HOOD LATCH

Arthur Claud-Mantle, Trumbull, Conn., assignor
to The Bassick Company, Bridgeport, Conn., a
corporation of Connecticut

Application July 20, 1946, Serial No. 685,027

9 Claims. (Cl. 292—305)

1

This invention relates to hood latches, and more particularly to those in which the automobile hood is of the alligator type, the lid of the hood being liftable from the front of the car.

One of the objects of the invention is to provide an improved hood latch of the type in which the lid carries a depending latch member which is adapted to be gripped and held within a gripping device carried by the lower stationary part of the hood.

Another object is to provide for very secure fastening of a latching member in the form of a latching post or shank, the latching member being firmly held against movement or play during the travel of the vehicle.

Another object is to provide improved means for acting upon and holding the latching post or like member and for effecting its release when it is desired to open the hood.

In the accompanying drawings:

Fig. 1 is a side elevation with parts broken away and with some parts in section, showing a hood latch embodying the invention, the latch being in the latched position;

Fig. 2 is an elevation with some parts broken away and some parts omitted, showing the latch illustrated in Fig. 1, looking from the front end of the car;

Fig. 3 is a section on line 3—3 of Fig. 1;

Fig. 4 is a section on line 4—4 of Fig. 3;

Fig. 5 is a section on line 5—5 of Fig. 2;

Fig. 5^a is a somewhat diagrammatic view not drawn to scale, showing the operation of the mechanism of Fig. 5 when the latch is released;

Fig. 6 is a section on line 6—6 of Fig. 2;

Fig. 7 is a view similar to Fig. 6 with parts omitted, showing the position of the elements during the releasing movement of the latch;

Fig. 8 is a vertical sectional view showing the position of the parts carried by the fixed part of the hood, when the lid is in the lifted position;

Fig. 8^a is a sectional view showing certain parts illustrated in Fig. 8 as they appear when the latch is in the released position for permitting disengagement of the latching post;

Fig. 9 is a bottom plan view of the parts shown in Fig. 8;

Fig. 10 is a view similar to Fig. 5 illustrating the action of the device when the latching post is somewhat twisted;

Fig. 11 is a section looking toward the rollers of Fig. 10 from the ends; and

Figs. 12 and 13 are views similar to Figs. 10 and 11 illustrating another condition hereinafter described.

2

In the embodiment selected for illustration, the automobile hood is of the alligator type, having a lid which is liftable from the front end of the car and has a hinge located adjacent the rear end of the engine enclosure. The latching mechanism includes a depending latching member generally in the form of a post carried by the lid adjacent the front end of the lid and adapted to be engaged by a gripping device located within the upper part of the stationary member of the engine enclosure. In this form, the latching post is fixed to a transverse mounting plate carried by the lid, and the gripping device is carried by a mounting plate supported in and extending transversely of the lower stationary hood member. The gripping device is constructed to receive and center the latching post when the lid is lowered, and the usual spring is employed in association with the two hood members, acting to separate them to a certain extent as soon as the latch is released. There is also preferably associated with the latching mechanism a safety hook or other safety device acting to limit lifting of the lid when the safety device is in the normal or active position. The gripping device for gripping the latching post and holding the lid in the closed position has, of course, associated therewith means whereby the latch can be released, and it is preferred to have the releasing means operable from the interior of the car through the use of a suitable member, such as a flexible pull member.

In the drawings, the lid is shown at 20, the lower hood member at 21, the mounting plate carried by the lid at 22, the mounting plate on the other hood member at 23, the latch post carried by member 22 at 24, and the lid-lifting spring at 25. The member 24 is preferably constructed in the manner hereinafter described. The gripping device carried by the mounting plate 23 is indicated generally at 26. A pull cable leading from the gripping device to the interior of the car is shown at 27, and an operating knob fixed to the pull cable within the interior of the car is shown at 28. The safety catch previously mentioned is shown at 29. In the form shown, this catch is provided with a hook and is pivoted to the plate 22 and adapted to engage in the usual manner under a portion of a rib 41 (to be hereinafter described) when the hook is in the normal position. The hook is manipulable by means of a manipulating arm or pad 29^a.

The latching post 24 is preferably of somewhat larger cross section adjacent its upper end than

adjacent its lower end, and at its upper extremity it is preferably provided with an enlargement or head 30 that is secured to plate 30^a in any suitable manner, as by riveting or upsetting. The spring 25 is a helical spring which surrounds the post 24, and has its lower end received in a cup 31 which is slidably mounted on the post and is adapted to take up against the upper part of the gripping device 26 when the lid is in the latched position, as shown in Fig. 3, at which time the spring is under considerable compression.

That portion of the post 24 which engages within the gripping device 26 is preferably flattened in cross section so as to have opposite substantially flat faces, and is tapered inwardly and upwardly, and preferably the cross section of this portion of the latching member is elongated in a direction lengthwise of the hood. The opposite larger faces are adapted to be engaged by gripping elements carried by the gripping member 26, as hereinafter described. The front and rear end surfaces provided on the flattened part of the latch post are preferably slightly rounded, as shown in Figs. 4 and 5, but not necessarily so.

The gripping member 26 in this form of the device comprises a box-like part in which are located the gripping elements to grip the post at opposite faces. In the form shown, the box-like member is constructed of sheet metal and has a top wall 32, a front wall 33, a rear wall 34, and a bottom wall 35. This box-like member also has in this embodiment a relatively fixed side wall 36 and a relatively movable opposite side wall 37, this side wall 37 serving as a part of the latch-releasing means, as hereinafter described.

The upper wall 32 of the box is provided with a slot 38 which receives the latch post with some clearance to permit freedom of movement when the lid is opened. Associated with the upper wall 32 is a centering device tending to locate and center the latching post when the lid is lowered. In the form shown, this centering device is provided by fixing a metal plate 39 in position upon the wall 32, said plate having bent-up longitudinal centering ribs 40 along the sides of the slot 38. The ribs 40 may be formed integral with transverse strengthening ribs 41 on the plate 39, as in the example shown. When the lid is in the latched position, the spring cup 31 rests on the ribs 40.

With in the box above described are located gripping elements adapted to hold the latching post by engaging the previously mentioned engaging faces. These elements comprise spring-pressed rollers which are mounted so as to be movable in an up-and-down direction. The element at one side of the post is indicated at 42 and the other element at 43. The element 42 is adapted to cooperate with the side wall 36 as hereinafter described, and the element 43 with the side wall 37. The element 42 comprises in its structure a gripping roller 44, and the element 43 comprises a gripping roller 45. The two elements are in this case of identical structure, each roller having trunnions 46 at the respective ends adapted to move in clearance slots or recesses in the front and rear walls of the box, and each element also comprising a shank 47 having a fork-shaped head 48 engaging a reduced roller portion 49 intermediate the ends of the roller in the manner shown in Fig. 5, the fork engaging the roller from beneath. Each roller support has its shank protruding through a slot 50 in the bottom of the box, and between the bottom of the box and the fork-shaped head on the shank is a compression

70
75

spring in the form of a coil, as indicated at 51, said spring normally holding the associated roller in a predetermined upper position as, for example, in engagement with the top wall of the box, as shown in Fig. 8.

Referring to Fig. 2, it will be observed that the right-hand roller has its forward trunnion received in a slot 52 in the forward wall of the box, while the trunnion of the left-hand roller is in a recess 53. The rearward wall of the box is constructed similarly to the forward wall as regards the provision of these clearance recesses.

As the rollers move upwardly in the box, they also move toward each other, their movement being along upwardly converging lines. In the present embodiment, this upwardly converging movement is caused by the fact that the rollers travel in engagement with the adjacent side walls of the box, which walls are formed at their upper portions to provide a slight incline, as shown, for example, in Fig. 8. The left-hand roller of Fig. 8 is in engagement with an inclined wall portion 54 on wall 36, and the right-hand roller is in engagement with an inclined portion 55 on wall 37. The wall 36 is, in this instance, a stationary wall, but the wall 37, on the other hand, is a movable wall, the same being pivoted to the box so as to be adapted to swing to one side for purposes of releasing the latch. In this case, the wall 37 is hinged or pivoted to the bottom of the box by having lug portions 37^a provided thereon which engage slots in the box bottom in a manner to hinge the wall so that it can be moved outwardly from the position shown in Fig. 3, swinging on the hinge connection. In the form shown, an upright shaft 56 is mounted outside of the wall 37, said shaft having a bearing 57 in an extension on the upper wall of the box and having a bearing 58 in an extension of the bottom of the box. The shaft 56 carries at its upper part a rigid member in the nature of a cam, indicated at 56^a, said cam having a periphery which for the most part is round but is provided with a flat surface 59. The round portion of the cam periphery is adapted to engage the external surface of wall 37 to hold the wall stationary in a position in which it will force the right-hand roller (Fig. 8) inwardly. A spring 60 acts on the shaft 56, so that normally the wall 37 will be held in the position just mentioned. The spring 60 may be a coil spring, the lower coils of which frictionally engage the shaft 56. As shown, this spring also has a lower extremity engaging a notch 61 in shaft 56, although this engagement may be omitted if it is desired to render the spring adjustable as to tension by rotation of the shaft. The spring has an upper extremity which, in this example, is extended across one of the box walls in abutting relation thereto, as shown in Fig. 1. Shaft 56 may be turned in opposition to the spring for purposes of releasing the latch, by means of an operating arm 62 suitably secured as by riveting to the upper end of the shaft, said arm being connected to the forward end of the pull cable 21 previously mentioned. When the cable is pulled, the arm 62 and shaft 56 are turned to a position in which the flat 59 is opposed to the wall 37, and this permits movement of said wall to release the latch.

In the operation of the device, the latching post 24 when the lid is lowered enters the slot 38 and enters between the opposite rollers and presses them downwardly from the position of Fig. 8 to the position of Fig. 3. For accomplishing this purpose, the lower end of the post is tapered

to an edge, as shown at 24^a, whereby the post wedges the rollers apart, and as they are wedged apart they move downwardly along their respective inclined guiding surfaces. The springs acting on the rollers press them upwardly so that, when the post is in its lowermost position, the rollers are firmly held in wedged engagement with opposite faces of the post. In this manner, the post is very strongly gripped and held without there being any play or movement between the latching post and the frame of the gripping device. The lid is, therefore, very strongly held in the closed position, and vibration due to the movement of the vehicle will not cause noise or undue wear in the latching means.

When it is desired to raise the lid, the knob 28 is pulled, which results in the turning of the shaft 56 to the releasing position. As soon as the cam 56^a is turned counterclockwise with respect to Fig. 5, the wall 37 is free to swing outwardly on its lower hinged mounting. This provides lateral clearance for the adjacent roller 45 and lateral clearance for the latching post, as indicated in an exaggerated manner in Fig. 5^a, so that the lifting spring 25 can immediately come into play, after which the lid is opened in the usual manner. As the latching member leaves the gripping box, the rollers move up to the positions shown in Fig. 8.

It is understood that, inasmuch as the lid is pivoted at the rear of the hood, the latch post, in moving to and from the latched position, swings in an arc of relatively long radius. The latch structure described is one well adapted for use under such conditions, accommodating itself to the swinging movement of the post and enabling the post to be effectively gripped as it moves downwardly through the lower plate element when the hood is being closed. In doing this the lower end of the post enters the space between the rollers and wedges them apart and moves them downwardly to some extent against the upward pushing action of their springs.

It is definitely of advantage to have the longer axis of the latching member shank cross section arranged generally in line with the longitudinal axis of the hood, for this allows for some inaccuracy in the locating of the hinge axis of the lid without interfering with the effective gripping of the latching member shank. As will be noted from Fig. 6, the slot 38 is of sufficient length to give ample clearance for an accurately positioned shank at both of the lateral edges of the shank. In the form shown, the clearance is greater in these regions than adjacent the side faces of the shank. The rollers engage the side faces of the shank over a substantial area, and in this way the gripping effect is increased. In the form shown, the elongation of the shank cross section is somewhat greater at the extremity of the shank than it is in the regions where the rollers engage the shank (Fig. 6), in order to retain the spring cup on the shank when the lid is open.

The construction described is also of advantage in that, if the shank or post is somewhat twisted in a horizontal plane as placed upon the lid, the rollers will nevertheless engage it and grip it effectively. This condition is illustrated in Figs. 10 and 11, and it will be noted that under these conditions the rollers are free to swing in planes which are at angles to the vertical longitudinal median plane of the hood in order to conform to the respective faces of the shank. Another condition which may arise, and which is compensated for in the improved construction, is illus-

trated in Figs. 12 and 13. Here the opposite side faces of the shank are out of parallelism with each other, but nevertheless the rollers can conform to the respective gripping surfaces on the shank.

In Figs. 10 to 13, inclusive, the supports for the rollers are omitted, but it will be understood that suitable spring-pressed supports are used, such as the supports previously described, provided with fork-shaped heads engaging reduced portions or neck portions of the rollers intermediate of the ends of the rollers. By referring to Fig. 5, for example, it will be noted that the forks 48 engage the reduced intermediate portions of the rollers with a certain amount of lateral clearance, and by this arrangement it is possible to support the roller resiliently between the roller ends, and at the same time permit tilting of the roller along its inclined contacting and guiding surface, if it is necessary for the roller to tilt in order to conform itself to the surface of the latching post.

It is very important in a device of this kind to overcome play when the latching member is in the latched position, with the noise and wear that result from the looseness of the parts. It is also important to provide against improper action of the latch as a result of slight inaccuracies in the hinging of the lid and in the placement of the latch members and their supporting parts relatively to the hood members. The device as herein described admirably meets these conditions, and at the same time it is relatively simple in structure and relatively inexpensive.

While, as shown herein, the members engaging substantial lateral areas of the latching shank are guided in their upward converging movements by walls of the box structure in which said members are received through direct engagement of the working surfaces of these members with the box walls, other guiding means may be used in some cases.

Only one embodiment is shown in the drawings, but it is to be understood that various changes in the organization of parts and in the details may be made without departing from the principles of the invention or the scope of the claims.

What I claim is:

1. In a hood latch, a rigid post-like latching member adapted to be carried by the lid of the hood, and a gripping means adapted to be carried by the lower part of the hood, said gripping means comprising in its structure a box into which the latching member can move from above, and separate rolling gripping elements in said box guided by opposite lateral walls of the box adapted to engage the latch member from opposite sides of the latter, one of said lateral walls of said box being movable to release one of said gripping elements and thereby release the latching member.
2. In a hood latch, a rigid depending post-like member adapted to be carried by the lid of the hood and having a flat side surface, and a gripping means for said member adapted to be carried by the lower stationary part of the hood, said depending member having a substantially flat side surface and said gripping means including a substantially horizontal spring-pressed roller for engagement with the flat side surface of the depending member, said roller being guided in a converging plane with reference to the median plane of the depending member, and the roller being tiltable so that one end is higher than the other.
3. In a hood latch, a rigid depending post-like latching member adapted to be carried by the lid,

a box adapted to be carried by the lower part of the hood having an upper slot into which said post-like member can enter, said box having lateral walls with inclined guiding surfaces thereon adjacent the upper part of the box, and gripping devices guided by said guiding surfaces comprising gripping rollers engageable with the latching member from opposite sides of the latter, and spring-pressed forked shanks disposed beneath the rollers and urging them upwardly in converging planes with respect to the median plane of the latching member and engaging reduced neck portions intermediate of the ends of the rollers in a manner to permit tilting of the rollers in the planes in which the respective rollers are guided, one of the lateral walls of the box being displaceable to release the latch.

4. In a latch for securing a lid to a hood, the combination of a rigid depending latching member within the forward end portion of the lid in the form of a post of elongated flattened cross section, said post being elongated lengthwise of the hood, a plate member fixed in the lower hood member having a slot into which the post enters and in which the post moves downwardly, and gripping rollers below said slot adapted to engage the respective side faces of the post to grip and hold the post, said rollers being pressed upwardly by springs and guided in upwardly converging planes and arranged to be wedged apart and moved downwardly by the post as the post moves to the latching position, said rollers being guided by and moving in a box structure arranged below said plate, and said box structure having a movable lateral wall acting as a support for one of the rollers which can be shifted to release the latch.

5. In a latch for securing a lid to a hood, the combination of a depending latching member within the forward end portion of the lid having opposite relatively wide side faces, a plate member fixed in the lower hood member having an aperture into which the latching member enters and in which it moves downwardly, and gripping rollers below said plate member adapted to engage the respective side faces of the latching member, said rollers being guided in upwardly converging planes and pressed upwardly by springs and normally engaging the under surface of said plate member at opposite sides of its aperture and in partially underlying relationship to said aperture and arranged to be moved downwardly to latching position by the latching member as the latter descends, and means for releasing the latch member by the outward displacement of one of the rollers with respect to the latch member.

6. In a latch for securing a lid to a hood, the combination of a depending latching member fixed within the forward end portion of the lid and having opposite relatively wide flat sides, a plate member fixed in the lower hood member having an aperture into which said latching member enters and in which said member moves downwardly, a box structure beneath said plate member, and gripping rollers for engaging the respective flat sides of the latch member pressed upwardly by springs within said box structure

and guided by opposite lateral walls thereof in upwardly converging planes and normally in contact with the lower surface of said plate member, one of said lateral walls being provided with a lower hinge so that it can be swung away from its associated roller.

5 7. A hood latch comprising a plate provided with an aperture to receive a latch member, a box structure arranged beneath and connected to said plate member and having a bottom and side and end walls, and gripping rollers within said box structure pressed upwardly by springs and guided in upwardly converging planes by opposite walls respectively of said structure and normally in contact with the lower surface of said plate member at opposite sides of said aperture, one of said opposite walls being mounted so that it can be moved away from its associated roller to release the latch member, and a device releasable from a distance for holding said wall in the operative or latching position.

10 8. A hood latch comprising a plate provided with a slot to receive a latch member of flattened cross section, a box structure arranged beneath and connected to said plate member and having a bottom and side and end walls, gripping rollers within said box structure at opposite sides of said slot pressed upwardly by springs and guided in upwardly converging planes by opposite walls 15 respectively of said structure and normally in contact with the lower surface of said plate member, one of said opposite walls being hinged at its lower part so that it can be swung away from its associated roller to release the latch member, and a spring-pressed cam device releasable from a distance for holding said hinged wall in the operative or latching position.

20 9. A hood latch comprising a plate provided with an aperture to receive a latch member, a box structure beneath and connected to said plate member and having a bottom and side and end walls, gripping rollers within said box structure pressed upwardly by springs mounted on shanks extending through the bottom of the box 25 structure, said rollers being guided in upwardly converging planes by opposite walls respectively of said structure, one of said opposite walls being mounted so that it can be moved away from its associated roller to release the latch member, and a device releasable from a distance for holding said wall in the operative or latching position.
